UNITED STATES PATENT OFFICE.

KARL H. HANSEN, OF PITTSBURGH, PENNSYLVANIA, ASSIGNEE TO ORENSTEIN-
ARTHUR KOPPEL CO., OF BERLIN, GERMANY.

DUMP-CAR.

1,084,271.

Specification of Letters Patent.

Patented Jan. 13, 1914.

Application filed February 20, 1911. Serial No. 609,793.

To all whom it may concern:

Be it known that I, KARL H. HANSEN, a subject of the Emperor of Germany, resident of Pittsburgh, in the county of Allegheny and State of Pennsylvania, have invented a new and useful Improvement in Dump-Cars; and I do hereby declare the following to be a full, clear, and exact description thereof.

10 My invention relates to dump cars of the tilting body type.

The object of my invention is to provide a dump car of this type in which the body of the car in dumping travels outward 15 whereby the body is thrown farther away from the end frame which permits of a larger dumping angle and at the same time makes it possible to reduce the height of the car which is a great point of advantage 20 in the loading of such cars.

In the accompanying drawing Figure 1 is a side elevation of my improved dump car partly in section; Fig. 2 is an end view partly in section; Fig. 3 is a plan view of 25 the supporting member on the truck.

In the drawing the numeral 2 designates a suitable truck carried by the wheels 3, the truck being of any desired construction and as it forms no part of my invention, it will 30 not be necessary to describe the same in detail.

Riveted or otherwise secured to the truck 2 at suitable intervals are the supporting members 4. These supporting members may 35 be formed of cast steel or other suitable metal, and said members are provided with the central circular recesses 5 extending in direction longitudinal of the truck, and sloping from said recesses 5 are the rocking 40 faces 6. The rocking faces 6 merge into the recesses 7 which are formed in the walls 8 of the supporting member 4, and beyond the recesses the inner walls bulge inwardly as at 9.

45 The upper supporting members 10 are riveted or otherwise secured to the central sills 11 of the car-body and said upper supporting member is provided with the semi-circular bearing 12 which is adapted to engage the recess 5 in the lower-member 4. At opposite sides of the bearing 12 are the 50 rocking faces 13 which are adapted in the dumping of the car to engage the rocking faces 6 of the lower member. The outer 55 edges of the upper member are provided

with a rounded portion 14 which is adapted to fit in and engage the recesses 7 of the lower member. The upper member 10 is further provided with the recesses 15 which are adapted to fit over and engage the rounded portions 9 of the walls of the lower member during the dumping operation.

The space or opening formed between the walls of the lower member is made just large enough to conveniently receive the upper member, so that when the upper member is in normal position the body of the car may be lifted vertically to be disengaged from the lower member without the removal of any hinge pins, bolts or other parts.

70 The chains 16 connect the body of the car with the truck to prevent the dumping of the car until the point of dumping has been reached, or during the loading of the car.

The sides of the car form the doors 17 which are opened automatically by suitable lever mechanism which forms no part of my present invention.

75 The operation of dumping my improved car is as follows: The chain 16 is released and force is applied to dump the car in the direction desired. In the first movement of the car in dumping, the turning will be done on the bearings 12 engaging the recesses 5 and in this way the starting resistance is readily overcome, owing to the car turning on a single hinge point. When this starting resistance has been overcome the body will have received a dumping momentum, whereupon the rocking faces 6 and 80 13 of the supporting members engage each other and this permits of the outward travel of the body of the car, while at the same time the portions 14 of the upper member enter the recesses 7 of the lower member. In this way the members are interlocked so that it is practically impossible to remove the body from the underframe, this eliminating the possibility of the body accidentally leaving the underframe, which is a great advantage, as the rough usage to which such cars are subjected and the rough tracks on which they are run very often causes the body to be thrown off the underframe. Furthermore as stated above, the engagement of 90 the rocking faces permits the body of the car to move farther outward in the dumping operation and as a consequence, it is possible to make the car-body lower and yet 95 get the same dumping facilities. The re-

100 105 110

duction in the height of the car is a great advantage where the cars are loaded by hand, as it brings the car nearer the ground and the shoveling of the material into the car is made easier.

This car has many advantages over the ordinary dump cars where a single hinged point is employed which does not permit of any outward movement of the body with reference to the truck in tilting and the large dumping angle cannot be obtained as in my invention.

By my invention I combine the advantages of readily overcoming the starting resistance together with the outward movement of the car which allows a larger dumping angle.

What I claim is:

1. In a dump car, the combination with a suitable truck, a supporting member having a central longitudinal hinge recess, downwardly inclined rocking faces at either side thereof and terminating in lateral recesses in the walls of said support, a body, a supporting member connected to said body, a central longitudinal hinge portion on said supporting member engaging said central recess in said lower member to form a hinge connection for initial rocking of the body, said upper member having upwardly inclined rocking faces adapted to engage the rocking faces of said lower member and portions adapted to engage within the lateral recesses in the sides of said lower member.
2. In a dump car, the combination with a suitable truck, of a supporting member having a central hinge recess, downwardly inclined rocking faces at either side thereof and terminating in lateral recesses having overhanging side walls, a body, a supporting member connected to said body and having a central hinge portion engaging the

central recess in said lower member to form a hinge connection for initial rocking of the body, said upper member having upwardly inclined rocking faces adapted to engage the rocking faces of said lower member, the rocking faces of said upper member being laterally extended to form projections adapted to engage beneath the overhanging walls of the recesses in the sides of said lower member, the spaces between the recessed side walls of said lower member being greater than the outside width across the lateral projections of said upper member whereby the car body may first swing on its hinged connection and then move laterally during the dumping operation to deliver the load well outside of the running gear of the car.

3. In a dump car, the combination with a suitable truck, of a supporting member having a central hinge recess, downwardly inclined rocking faces at both sides thereof and terminating in recesses having overhanging walls, a body, a supporting member connected by said body having a central hinge projection to form a central hinged connection with said central recess in said lower member to form a hinge for initial rocking of the body, said upper member having upwardly inclined rocking faces adapted to engage the rocking faces of said lower member and having portions adapted to engage beneath the overhanging walls of the recesses in the sides of said lower member and having recesses in its side walls adapted to hinge upon the overhanging side walls of said lower member.

In testimony whereof, I, the said KARL H. HANSEN, have hereunto set my hand.

KARL H. HANSEN.
